PROCESS FOR THE DESTRUCTIVE DISTILLATION OF SOLID CARBONACEOUS MATERIALS

Filed Oct. 16, 1922

UNITED STATES PATENT OFFICE.

PAUL DVORKOVITZ, OF LONDON, ENGLAND.

PROCESS FOR THE DESTRUCTIVE DISTILLATION OF SOLID CARBONACEOUS MATERIALS.

Application filed October 16, 1922, Serial No. 594,865, and in Great Britain November 17, 1921.

This invention relates to the known process of treating coal or other solid carbonaceous matter, for obtaining liquid distillate products therefrom in which process the 5 said coal, or other carbonaceous matter, is heated in a closed retort by contact with hot gas and afterwards the vapors obtained are condensed, the operation being conducted in apparatus comprising means for heating the 10 gas to be supplied to the interior of the retort and a condenser in which the volatile products passed from the retort are condensed, and obtained in the liquid form.

It is known that, in treating petroleum 15 residues by means of superheated steam, the temperature of the steam plays a very important part in the products obtained. If the temperature of the steam be higher than is required for vaporizing the heavy oils 20 decomposition takes place and the quality of the products is deteriorated, while if the steam be of a lower temperature than is required the heavy parts of the oil do not evaporate and are left in the residue. Thus 25 the regulation of the temperature of the steam is of great importance. The same applies to the treatment of coal, or other carbonaceous matter, for the purpose of extracting oils of the paraffin series, by means 30 of heated hydrogen, water gas, and the like.

It has been proposed to extract volatile matter such as benzole, toluol, and other hydrocarbons of the aromatic series from coal by passing hot purified gas brought to 35 a controlled temperature of between 600 and 1000 degrees Fahrenheit (approximately between 316 and 538 degrees centigrade), or to a higher temperature, into intimate contact with every particle of the coal contained 40 in a closed retort; in this process it is proposed to heat the gas to the required temperature in a furnace, separate from the retort, and to admit the gas alternately at the bottom and at the top of the retort containing the charge.

My invention has for its especial object to treat the coal, or other carbonaceous matter, in an improved way so that oils of the paraffin series, as distinguished from hydrocarbons of the aromatic series, are obtained therefrom in an efficient and economical manner. According to my invention the heated gases are admitted only to the upper end of the retorts from a heater which is 55 separate from the retorts, the said gases being for instance, hydrogen, water gas, pro-

ducer gas, or ordinary coal gas, the temperature of which is controlled so that the heat produced in the retorts is such as will liberate from the charge in the said retorts only, 60 or mainly, the desired oils of the paraffin series the heat required for this purpose being not higher than about 500 degrees centigrade. I have found that the temperature of the charges in the retorts should not 65 exceed about 500 degrees centigrade the lower temperature being of course only such as will distill off such amount of the oils of the paraffin series as will make the process sufficiently profitable.

Various qualities of coal, or other carbonaceous matter, require different temperatures to extract the oils of the paraffin series therefrom; for example, lignite coal requires 70 lower temperature than does gas coal or steam coal, to produce the best results.

The regulation of the temperature of the gas admitted to the retorts, containing the coal, or other carbonaceous matter, is, therefore of great importance, and the temperature is very conveniently obtained by providing a heater separate from the retorts, in which heater the gas can be heated to the extent required to produce in the retorts the aforesaid temperatures employed in accordance 80 with my invention, but I make no claim to the heater per se.

My invention may be carried out, for example as follows:—

Although I do not limit my invention to the treatment of coal, I will, for brevity of description, presume that the carbonaceous matter to be treated is coal.

In carrying out my invention I subject the coal, while it is in a closed vertical, or inclined, retort, or vessel, to the aforesaid temperature not exceeding about 500 degrees centigrade which will vaporize, or separate, only, or mainly, the oils of the paraffin series from the said coal. The heating agent, such for example as hydrogen or water gas, or producer gas, or ordinary coal gas, is heated in the heater to a temperature to maintain in the retorts the requisite temperature, as aforesaid, for treating the charges, the said heating agent being admitted only to the top of the charge. The heat applied will vaporize, or separate from the coal the constituents which are acted upon by the heat applied as aforesaid these constituents being light oils of the paraffin series (that is to say, oils of the paraffin

- series having a comparatively low specific gravity) which will pass downward towards the outlet and, in their descent, the said constituents will dissolve and carry out with them, from the remainder, or lower parts, of the charge, the heavy oils of the paraffin series and such products will pass out by the outlet at bottom leaving in the retort, or vessel, the denser constituents and carbon which can be treated in the same retort, or vessel, or be removed and treated in another retort, or vessel, in any known, or suitable way, for the obtainment of products therefrom.
- 15 I may, for example, carry out my process as described and then, after I have obtained the products desired, I may treat the matter remaining in the retorts at a higher temperature in accordance with the products which it may be desired to obtain therefrom.

The retort, or vessel, employed for the purposes of my invention, may be made of any ordinary, or suitable, material such, for instance, as cast-iron and be provided with any usual, or suitable adjuncts. The outlet for the products obtained is preferably somewhat inclined upwards from the side of the lower end of the interior of the retort, or vessel, to prevent the said outlet from being clogged by solid matter from the retort, or vessel.

From the retorts the vapors pass to a series of condensers from which the products of condensation can be removed separately, as desired.

The accompanying drawing represents in elevation partly in section, in Figure 1, a plant suitable for the purposes of my invention which is however not limited to the employment of the particular form and details of the various parts illustrated. Figure 2 is a horizontal section on the line $\alpha-\alpha$ Figure 1.

45 The retorts into which the coal, to be treated is charged are marked A. They may be in any suitable number and are shown as being of greatest cross-sectional area at top narrowing down gradually to the lower end. To enable the heat to penetrate the charges in the retorts they are preferably of small cross-sectional area, having one horizontal dimension considerably shorter than the other, and to enable the charge to receive a comparatively large charge without interfering with the due penetration of the heat, I prefer to make them of elliptical, or equivalent, formation as shown in Figure 2. The said retorts are provided with charging hoppers α with duplex valves α^2 α^3 of the usual, or any suitable, kind which will permit of charging without putting the insides of the retorts in communication with the outer air. The retorts are set in the retort chamber B, which

communicates at top with the furnace C, by the passage b , controlled by a damper b^2 , the lower part of the chamber B communicating at b^3 with an uprising tube, or chimney, D. The pipe E, provided with a valve at e , leads from a source of supply of gas to be admitted to, and internally heat, the retorts A,—the said pipe E passing in a coil, or convolutions, E^2 through the upper part of the furnace C and thence, by branches E^3 , E^4 , (controlled by valves e^3 , e^4) into the upper ends of the retorts A wherein the gas issuing therefrom will burn and, in conjunction with the external heating by products of combustion from the furnace C, produce the temperature necessary to liberate from the charge the required constituents which will pass downwards and, owing to the retorts being heated by gases which are hottest at the upper ends of the retort 85 and owing to the currents of gases and vapours inside the retorts being constantly in a downward direction the said constituents (such as paraffin oil, and gas) will, as soon as they are formed, pass rapidly downwards without danger of their becoming carbonized and will pass out from the retorts by the upwardly inclined outlet passages a^4 into a pipe a^5 , leading to condenser pipes F, F, which dip into closed tanks G which receive the liquefied constituents whilst any gas, or vapours, will pass off by the pipe F^2 , the liquid constituents from the tank G, being drawn off therefrom separately if so desired, or being run therefrom through outlet pipes g , and away by the pipe g^2 common to all, or any number of them.

The retorts can be emptied from solid matter, such as coke by removing the bottom covers and raking out at intervals or in any other suitable way.

What I claim is:—

1. A process for recovering light oils of the paraffin series from solid carbonaceous material, which comprises heating an elongated upright carbonaceous mass of relatively small cross sectional area on the one hand by external gases which are hottest at the upper end and pass downward around the mass and on the other hand by downwardly drafted internal carrier gas at elevated temperature, the heating of the mass being so regulated as to drive off therefrom substantially only the desired oils of the paraffin series, and leading off from the bottom of the mass to a condenser the carrier gas and the entrained vapor of the paraffin oil.

2. The process for destructively distilling solid carbonaceous material in a closed vertical retort and recovering oils of the paraffin series therefrom, consisting in heating said material both by the combustion gases of a furnace and by heated carrier gas, and sub-

- sequently cooling the resulting vapors; the combustion gases passing downward around the outside of the retort, the heated carrier gas passing downward through the carbonaceous substance inside the retort, and the temperature being maintained below that at which the heavier constituents of the mass volatilize.
3. The process for destructively distilling solid carbonaceous material in a closed vertical retort and recovering oils of the paraffin series therefrom, consisting in heating said material both by the combustion gases of a furnace and by heated carrier gas, and sub-
- sequently cooling the resulting vapors; the combustion gases passing downward around the outside of the retort, the carrier gas passing downward through the carbonaceous substance inside the retort, the products of distillation being withdrawn from the retort in an upward direction, and the temperature being maintained below that at which the heavier constituents of the mass volatilize.

In testimony whereof I have signed my name to this specification.

PAUL DVORKOVITZ.
